UNITED STATES PATENT OFFICE

113,765

DESIGN FOR A CABINET FOR INTER-BUILD- ING COMMUNICATION SYSTEMS

George Risk, Des Moines, Iowa

Application July 1, 1938, Serial No. 78,221

Term of patent 3½ years

To all whom it may concern:

Be it known that I, George Risk, a citizen of the United States and resident of Des Moines, Polk County, Iowa, have invented a new, original and ornamental Design for a Cabinet for Inter-Building Communication Systems, of which the following is a specification, reference being had to the accompanying drawing, forming a part thereof.

Fig. 1 is a front elevational view of my cabinet

for inter-building communication systems, showing my new design.

Fig. 2 is a side view of my cabinet for inter-building communication systems showing my new design.

I claim:

The ornamental design for a cabinet for inter-building communication systems, substantially as shown.

GEORGE RISK.
